Des. 218,243
Patented Aug. 4, 1970

218,243

COMBINED BOOK END AND VASE

Emil Mollik, 74 Glider Ave., Flanders Road,
Riverhead, N.Y. 11901

Filed May 22, 1969, Ser. No. 17,277

Term of patent 7 years

Int. Cl. D6—01

U.S. Cl. D33—3

FIG. 1

FIG. 2

FIG. 3

FIG. 1 is a front-elevational view of a combined book end and vase embodying my novel design;

FIG. 2 is a side view thereof; and

FIG. 3 is a top view of same.

The side not shown is a mirror image of the side shown in FIG. 2 while the back is plain and conventionally flat.

I claim:

The ornamental design for a combined book end and vase, as shown and described.
